GOBLET

Edgar M. Bottome, Moundsville, W. Va., assignor
to Fostoria Glass Company, Moundsville,
W. Va., a corporation of West Virginia

Application November 26, 1948, Serial No. 149,829

Term of patent 14 years

(Cl. D36—8)

To all whom it may concern:

Be it known that I, Edgar M. Bottome, a citizen of the United States of America, residing at Moundsville, in the county of Marshall and State of West Virginia, have invented a new, original, and ornamental Design for a Goblet, of which the following is a specification, reference being had to the accompanying drawing, forming part thereof, wherein:

The single figure is a side elevational view of a goblet showing my new design.

The goblet is circular and the dominant feature of the instant invention resides in the sur-

face ornamentation shown in full lines, which is repeated around the peripheral surface.

I claim:

The ornamental design for a goblet, as shown and described.

EDGAR M. BOTTOME.
